(57) **CLAIM**

The ornamental design for a perfume bottle, as shown and described.

DESCRIPTION

The patent or application file contains at least one drawing executed in color. Copies of this patent or patent application publication with color drawing(s) will be provided by the Office upon request and payment of the necessary fee.

FIG. 1 is a perspective view of the perfume bottle also showing the claimed colors being red and metallic gold. All the sides of the cap are metallic gold except for its front part, which is black. The base of the bottle is also metallic gold, including its bottom.

FIG. 2 is a front view thereof;

FIG. 3 is a right side view thereof, the left side being a mirror image thereof;

FIG. 4 is a rear view thereof; and,

FIG. 5 is a top view thereof.
